PRACTICE KEYBOARD

Joseph S. Tatnall, Gordon Heights, Del., assignor to Audiscope Corporation, a corporation of Delaware

Application April 1, 1948, Serial No. 18,451

9 Claims. (Cl. 84—467)

1

My invention relates to a practice key board simulating the appearance and action of the key board of a complete piano. Such devices are particularly intended for piano instruction and practice in situations where it would be impractical or undesirable to employ a full, tuned piano. For example, piano students may receive group instruction in finger movements, each being provided with such a practice key board, or expert players may employ them for exercise purposes, when a complete piano is not available or its sound might disturb others.

It is most important that such a practice key board be substantially identical in action or "feel" with the key board of a full, tuned piano, otherwise much of its value would be lost. Furthermore, it must be durable and yet inexpensive and light in weight, in order to assure its widespread use. It is the object of my invention to provide such a device that combines all of these desired characteristics.

The principal feature of my invention has to do with the particular means employed to produce a tension upon the keys of the practice key board, that is substantially identical with the tension under which the keys of a full, tuned piano are held, thereby to imitate closely the action or "feel" of the piano key board. Many attempts have been made to reproduce such tension by means of various types of metal springs, rubber bands, sponge rubber and the like, but none have proven to be as simple, durable and effective as the means which I have devised.

A further feature of my invention concerns the location of my novel tensioning means, whereby they also serve to hold the keys of my practice key board in proper alignment, despite the use of a loose pivot. Yet another feature resides in the manner in which such tensioning means are mounted in the practice key board, making it very easy to install and to replace them as desired. These features of my invention may be embodied in the practice key board singly and in combination to accomplish the object of my invention.

My novel tensioning means consist of short sections of rubber tubing, which are compressed axially as the keys of the practice key board are depressed. Such rubber tube sections are remarkably uniform and durable in action. It is possible to regulate the degree and kind of tension thereby exerted upon the keys, by varying their diameter, wall thickness or length. The type of resilient material employed, which need not necessarily be natural rubber, is also a factor,

but given any suitable resilient material, it is easy to reproduce precisely the desired kind and degree of tension by proper selection of the other factors mentioned.

5 As previously indicated, the location of my novel tensioning means within the practice key board is important for optimum results. I have found that by causing them to bear against the backs of the keys at a point below the pivot of the keys, they tend to push the keys forward against such pivot and to hold them in proper alignment, even though the keys fit loosely about said pivot. It is highly desirable from a manufacturing standpoint and from the standpoint of simulating the action of piano keys, to employ such a loose pivot.

I have found that my novel tensioning means can be very easily mounted upon a metal plate along the back of the practice key board, which 20 metal plate has a series of up-struck inner projections about which the rubber tube sections are simply fitted and to which they hold by their own resiliency. The up-struck projecting portions of the metal back plate serve to support 25 the rubber tube sections at exactly the desired locations. This is important, when one considers that a separate tensioning means is provided for each individual key, so that the action of one key will not affect that of any other. A great advantage achieved by this manner of mounting the tensioning means, is that they can be installed and replaced as desired simply by slipping them over the up-struck projections on the metal back plate.

30 In other respects my practice key board is of more or less conventional construction. It includes the usual set of long white and short black keys of the same dimensions as in the key board of a piano, except that ordinarily the practice key board is limited to but a few octaves, in order to reduce its length without unduly reducing its utility as a practice instrument. The keys are all pivoted on a single rod or shaft located near the back of the device, which is supported at several points along its length to assure ample rigidity. Cushioned stops are provided to limit the movement of the keys about the pivot and to render their action noiseless. A case is generally provided, which is similar in appearance to that surrounding the key board of a regular piano.

45 In the accompanying drawings, I have illustrated a preferred embodiment of my invention including the various features generally referred to above. In these drawings:

Figure 1 is a plan view of a portion (two octaves) of a practice key board according to my invention. The top portion of the usual case has been removed in order to show my novel tensioning means mounted upon the metal back plate;

Figure 2 is a sectional view on the line 2—2 of Figure 1 and;

Figure 3 is another sectional view of a portion of my device along the line 3—3 of Figure 2.

As shown by these drawings, the long white keys 10 and the short black keys 11 are supported at the back by a common pivot 12 which extends across the entire length of the key board. This pivot is preferably composed of a metal rod or a shaft which is supported at each end and at several points along its length to impart sufficient rigidity. It passes through holes in the keys and should fit rather loosely for ease in manufacture and assembly and for freedom of action of the keys. The arcs in which the keys may swing about the pivot are limited by the stops 13, 14, 15 and 16, which are composed of resilient material, such as a rubber tube, in order to render the key board soundless. The stops 13 and 14 limit the movement of the white keys 10, while stops 15 and 16 limit that of the black keys. The white keys 10 are provided with a projection 17 at the bottom front portion to act upon the stop 13. Stop 16 is located upon a raised base 18, in order that the black keys 11 may not be depressed below the desired point.

All of the keys 10 and 11 are provided with downwardly extending portions 19 at the back against which my novel tensioning means are caused to act. These tensioning means consist of short sections of rubber or like resilient tubing 20 and 21. Since the black keys 11 are shorter and swing through a greater arc than the white keys 10, it is best to compensate for these differences by employing resilient tube sections of slightly different diameters and wall thicknesses. In the key board shown, the tube sections 21 acting upon the black keys are slightly larger in diameter and have greater wall thickness than the tube sections 20 acting upon the white keys.

The method of mounting my novel tensioning means at the desired locations can best be seen from Figure 2. Up-struck projections 22 are provided in the metal back plate 23 by a simple stamping operation. These projections are of such width that the resilient tube sections will fit snugly thereover. No adhesive need be employed, thus greatly simplifying the task of installing or replacing the tensioning means. The projections 22 do not extend far enough within the resilient tube sections 20 and 21 to interfere with the tensioning action of the latter.

It should be noted that the tensioning means 20 and 21 are normally under sufficient compression to force the keys 10 and 11 against the stops 13 and 15, respectively. These tensioning means are centered in back of each individual key, thus tending to force it forward against the pivot 12. As a result, the tensioning means tend to keep the keys in proper alignment, even though a loose pivot is employed.

The case of my practice key board may be made of a single sheet of metal as shown, or the metal back plate 23 may be mounted within a separate wooden casing, if desired. Many other variations are, of course, possible without departing from the principles of my invention. The invention is not limited to the details shown and includes all

such modifications as are embraced within the scope of the appended claims.

I claim:

1. A practice key board comprising a set of pivotally mounted keys and tensioning means urging the front ends of the keys upwards, said tensioning means consisting of short, resilient tube sections fixedly supported at one end within the device which are compressed axially, when the front ends of the keys are depressed.

5 2. A practice key board comprising a set of keys, all mounted on a horizontal pivot, and separate tensioning means for each key urging its front end upwards, said tensioning means consisting of a short, resilient tube section fixedly supported at one end within the device which is compressed axially, when the front end of the key is depressed.

10 3. A practice key board comprising a set of keys, pivotally mounted near the back of the device, and short, axially compressed tube sections of resilient material fixedly supported at one end within the device and whose other ends bear against the backs of said keys below their pivot.

15 4. A practice key board comprising a set of keys, all mounted on a horizontal pivot rod near the back of the device, and a corresponding set of short, axially compressed tube sections of resilient material mounted upon a back plate, each tube section bearing against the back of a key below the pivot rod.

20 5. A practice key board comprising a set of keys, pivotally mounted near the back of the device, and short, axially compressed tube sections of resilient material mounted over inwardly projecting, up-struck portions of a metal back plate and bearing against the backs of the keys below their pivot.

25 6. A practice key board comprising a set of white and black keys, all mounted on a horizontal pivot rod near the back of the device, and a corresponding set of short, axially compressed, rubber tube sections, all fitting snugly over inwardly projecting, up-struck portions of a metal back plate, each tube section being centered in back of a key and bearing against a downwardly extending portion thereof.

30 7. A practice key board as claimed in claim 6, wherein the diameter and wall thickness of the tube sections bearing against the black keys are larger than those of the tube sections bearing against the white keys.

35 8. A practice key board comprising a set of keys, all pivotally mounted near the back of the device, and short, compressible, resilient members fixedly supported at one end within the device and whose other ends bear against the backs of said keys below their pivot.

40 9. A practice key board comprising a set of keys, all loosely mounted on a horizontal pivot rod near the back of the device, and a corresponding set of short, compressible, resilient members mounted at one end upon a back plate, the other end of each of said members bearing against the back of a key below the pivot rod.
